US00D764459S

(12) **United States Design Patent**
Kwong

(10) **Patent No.:** **US D764,459 S**
(45) **Date of Patent:** ** *Aug. 23, 2016

(54) **ELECTRONIC DEVICE**

(71) Applicant: **VTech Electronics, Ltd.**, Hong Kong (CN)

(72) Inventor: **Chin Fai Kwong**, Hong Kong (CN)

(73) Assignee: **VTECH ELECTRONICS, LTD.**, Tai Po, New Territories (HK)

(*) Notice: This patent is subject to a terminal disclaimer.

(**) Term: **14 Years**

(21) Appl. No.: **29/519,245**

(22) Filed: **Mar. 3, 2015**

Related U.S. Application Data

(63) Continuation of application No. 29/459,586, filed on Jul. 1, 2013, now Pat. No. Des. 723,549.

(57) **CLAIM**

The ornamental design for an electronic device, as shown and described.

DESCRIPTION

FIG. 1 is a front perspective view of my new design for an electronic device;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear perspective view thereof.

The dashed broken lines shown in the drawings represent portions of the electronic device that form no part of the claimed design.

1 Claim, 6 Drawing Sheets
